(57) **CLAIM**

The ornamental design for aircraft galley, as shown and described.

DESCRIPTION

FIG. 1 is a front view of the aircraft galley;
FIG. 2 is a front view of the aircraft galley showing vertically oriented wood grain surface treatment;
FIG. 3 is a front view of the aircraft galley showing horizontally oriented wood grain surface treatment; and,
FIG. 4 is a front view of the aircraft galley showing vertically oriented wood grain surface treatment.

The fragmentary showing of wood graining in FIGS. 2-4 is understood to be repeated throughout the surface(s) shown. The broken lines in the drawings depict portions of the article that form no part of the claimed design.

The dash-dot lines in the drawings depict a border of the aircraft galley that forms no part of the claimed design.

1 Claim, 4 Drawing Sheets

FIG. 1

FIG. 2

FIG. 3

FIG. 4
